F. CARRIER

BOTTLE CONTAINER

Filed Sept. 2, 1924

INVENTOR.
Fortunat Carrier

BY

Frank J. Donnelly
ATTORNEY.

UNITED STATES PATENT OFFICE.

FORTUNAT CARRIER, OF DETROIT, MICHIGAN.

BOTTLE CONTAINER.

Application filed September 2, 1924. Serial No. 735,286.

To all whom it may concern:

Be it known that I, FORTUNAT CARRIER, a subject of the King of England, residing at Detroit, in the county of Wayne and State 5 of Michigan, have invented a new and useful Improvement in a Bottle Container, of which the following is a specification.

My invention relates to a new and useful improvement in a bottle container and has 10 for its object the provision of a bottle container which will be simple in structure, economical of manufacture and highly efficient in use.

The invention relates particularly to a 15 container adapted for receiving and holding milk bottles which are delivered by the carrier and deposited, to be removed at a later time by the party to whom delivered. In view of the custom of delivering milk in 20 bottles in this manner, it has been found that the bottles are frequently purloined, and thus the party for whom the milk was intended is deprived of its use. The present invention provides a receptacle for the milk 25 bottle which is accessible to the carrier of the milk and may be automatically locked, after the carrier has deposited the full bottle in the container. To provide a container of this class, which will automatically lock 30 itself after the deposit of a full receptacle therein and be freely accessible previous to the deposit of a full container or bottle 35 therein is one of the objects of the invention.

Another object of the invention is the 40 provision in a container of this class of means for automatically locking the container upon the deposit of an article therein of sufficient weight and of preventing the locking of the container with the deposit 45 of an article of a certain weight and having a certain length.

Other objects will appear hereinafter.

The invention consists in the combination 45 and arrangement of parts hereinafter described and claimed.

The invention will be best understood from a reference to the accompanying drawings which form a part of this specification, and in which,

50 Fig. 1 is a front elevational view of the receptacle showing the door open,

Fig. 2 is a central, vertical, sectional view of the invention illustrating the door closed,

55 Fig. 3 is a plan view of the receiving member mounted in the container showing a portion in section.

The invention, in its preferred form, comprises a box or container, 7, having a suitable door 8 hingedly connected thereon and provided along the edges of the open side 60 with an inturned flange 9. Projected through the rear wall of the receptacle is an extension 10 of a stirrup, or U-shaped member, 11 adapted for receiving the articles placed in the container. The extreme 65 end 12 of the portion 10 is angularly turned, as shown in Fig. 2, and secured to the rear wall of the container, so that the stirrup 11 is permitted to swing slightly on its position of mounting. This member, together with 70 the portion 10 and 11, being formed from metal sufficiently resilient to allow a slight spring of the stirrup when weight is placed thereupon. As shown in Fig. 2, one leg 13 of the stirrup is provided with an opening 75 14 in which is positioned a horizontally extending rod 15 having an angularly turned portion 16 which extends vertically downwardly behind one of the flanges 9 and projected through suitable bearings 17 and 18 80 mounted upon the side wall of the housing, to permit vertical movement of the member 16. Projecting outwardly from the vertically extending rod 16 into parallel relation with the door 8, when the same is closed, is 85 a tongue 19, which is fixedly mounted upon the rod 16, so as to move vertically when the rod 16 is moved vertically. Mounted on the inner surface of the door 8 is a catch 20 so positioned as to engage the tongue 19 and 90 prevent the opening of the door, when the stirrup 11 is pressed downwardly. When the stirrup is in its normal position and no downwardly pressing weight is placed thereon, a closing of the door 8 will allow the 95 catch 20 to clear the tongue 19. The space between the legs of the stirrup is such that the neck of a milk bottle may be placed therein, the head or lip of the milk bottle serving to prevent the same from slipping 100 downwardly through the stirrup. The milk carrier, in delivering the milk, may open the door 8 and place the milk bottle in the stirrup 11, the full milk bottle having been placed in the stirrup 11, the same is pressed 105 slightly downwardly, so as to bring the tongue 19 into such a position as to engage behind the catch 20, as shown in Fig. 2, and thus prevent the opening of the door 8 from the exterior of the container. Fixedly mounted upon the rod 16 is a tongue having 110 a main body portion 21 provided with an

upwardly inclined edge 22 which inclines upwardly outwardly from the side wall of the container and terminates abruptly to form an outwardly extending tongue 23 to provide a shoulder for engagement with a key adapted for insertion in the keyhole 24. When the container is locked with the contents therein, the key inserted through the key-hole 24, will engage the tongue 23 and serve to raise the rod 16 upwardly to disengage the tongue 19 from the catch 20. Thereupon the door may be swung open, as desired.

The empty bottles may be placed in the stirrup without causing the door to lock when closed, the weight of the empty bottles being insufficient to overcome the tension of the stirrup sufficiently to move the tongue 19 downwardly into operative engaging position. However, it may be desired to use the container for the deposit of milk bottles of various sizes, and it has been found that the quart milk bottle, for instance, when empty is of greater weight than the half pint bottle when full. In order to provide a container which may be used with quart bottles and half pint bottles, it is necessary that the half pint bottle, when full, shall move the stirrup downwardly, so as to bring the tongue 19 into engagement with the catch 20. The mounting of the stirrup is so constructed as to permit the half pint bottle when full to automatically lock the door when closed. In order to prevent the empty quart bottle, when hung on the stirrup, from locking the container when the door is closed, I have secured to the floor or lower wall of the container, one end of a leaf spring 25, the other end of which is flexed upwardly so as to be in spaced relation to the floor or lower wall of the container. The distance between the stirrups and the leaf spring 25 is such that when a quart bottle is placed in the stirrup, it will rest upon the spring 25, and thus will not direct its weight downwardly against the stirrup, so that the tongue 19 will not be moved into engagement with the catch 20. When the full quart bottle is placed upon the stirrup, the weight, of course, will be sufficient to overcome the tension of the stirrup and the tension of the spring 25, so as to lock the door, when the same is closed. Half pint and pint bottles, being of such a length as to hang freely in the container, will not engage the leaf spring 25, so that their weight will, when the bottles are filled, serve to lock the door when it is closed, and when the bottles are empty, exert insufficient pressure downwardly to move the stirrup downwardly so as to bring the tongue 19 into engagement with the catch.

While I have illustrated and described the preferred form of structure, I do not wish to limit myself to the precise form of structure shown, but desire to avail myself of

such variations and modifications as come within the scope of the appended claims.

Having thus described my invention, what I claim as new and desire to secure by Letters Patent is:

1. A container of the class described, comprising a housing; a door mounted on said housing adapted for opening and closing; a receptacle receiving member mounted on one of the walls of said housing normally in horizontal position and adapted for movement into downwardly inclined position against the tension of its mounting upon the placing thereon of an article of predetermined weight; slideable means mounted on one of the walls of said housing and connected with said receiving member for automatically locking said door upon the closing of the same subsequently to the downward swinging of said receiving member, said door having an opening formed therein; and slideable means accessible through the opening in said door for raising said receiving member into horizontal position for unlocking said door.

2. A container of the class described comprising a housing adapted for the reception of bottles; a substantially U-shaped receiving member adapted for suspending bottles in said housing, said U-shaped member being swingable relatively to the floor of said housing; a door on said housing adapted for opening and closing; and slideable means mounted in said housing and connected with said U-shaped member for automatically locking said door upon the closing of the same subsequently to the placing on said U-shaped member of a bottle of sufficient weight for moving said U-shaped member downwardly relatively to its mounting beyond a predetermined point.

3. A container of the class described comprising a housing adapted for the reception of bottles; a substantially U-shaped receiving member adapted for suspending bottles in said housing, said U-shaped member being swingable relatively to the floor of said housing; a door on said housing adapted for opening and closing; slideable means mounted in said housing and connected with said U-shaped member for automatically locking said door upon the closing of the same subsequently to the placing on said U-shaped member of a bottle of sufficient weight for moving said U-shaped member downwardly relatively to its mounting beyond a predetermined point; and yieldable means mounted in said housing for engaging the bottom of said bottle for normally resisting the downward movement of the same, after the placement of said bottle on said U-shaped member.

In testimony whereof I have signed the foregoing specification.

FORTUNAT CARRIER.
